The ornamental design for a disposable liner for a cooler, as shown and described.

DESCRIPTION

FIG. 1 is a perspective view of a disposable liner for a cooler according to the present invention;

FIG. 2 is an elevational view of the front side of the disposable liner for a cooler of FIG. 1;

FIG. 3 is an elevational view of the rear side of the disposable liner for a cooler of FIG. 1;

FIG. 4 is an elevational view of the right side of the disposable liner for a cooler of FIG. 1;

FIG. 5 is an elevational view of the left side of the disposable liner for a cooler of FIG. 1;

FIG. 6 is a plan view of the top side of the disposable liner for a cooler of FIG. 1;

FIG. 7 is a plan view of the bottom side of the disposable liner for a cooler of FIG. 1;

FIG. 8 is an exploded, perspective view of the disposable liner for a cooler of FIG. 1 viewed from an upper perspective; and,

FIG. 9 is an exploded, perspective view of the disposable liner for a cooler of FIG. 1 viewed from a lower perspective. The broken lines in the drawings are unclaimed subject matter.
